UNITED STATES PATENT OFFICE.

ANDREW M. DORR AND JOSEPH SPANG, OF BOSTON, MASSACHUSETTS,
ASSIGNORS TO CHEMICAL AND ELECTRICAL ORE REDUCING COMPANY, OF WEST VIRGINIA.

APPARATUS FOR TREATING ORES.

SPECIFICATION forming part of Letters Patent No. 699,457, dated May 6, 1902.

Application filed February 19, 1902. Serial No. 94,829. (No model.)

To all whom it may concern:

Be it known that we, ANDREW M. DORR and JOSEPH SPANG, citizens of the United States, and residents of Boston, in the county of Suffolk and State of Massachusetts, have invented a new and useful Improvement in Apparatus for Treating Ores, of which the following is a specification.

Our invention relates to an apparatus for the treatment of ores, which has been designed more particularly with a view to its use in a process for the production of matte directly from the ore, which we have made the subject of an application, Serial No. 94,828, for Letters Patent of even date herewith, said process being a continuous reduction process involving the three steps of roasting, smelting the roasted ore, and purifying the smelted ore, in connection with the employment of a downdraft and a gas rich in oxygen which is injected into and supplied to the reduction-chamber and the matte-chamber of the furnace.

We will first describe in connection with the accompanying drawings the preferred construction and arrangement of the parts of the apparatus and will then point out more particularly in the claims those features of the same which we believe to be new and of our invention.

In said drawings, Figure 1 is a sectional elevation of the complete apparatus. Fig. 2 is a front elevation of the furnace. Fig. 3 is a perspective view of the molten-metal receiver. Fig. 4 is a rear elevation of the furnace. Fig. 5 is a top plan view of the same, and Fig. 6 is a longitudinal vertical central section of the furnace on enlarged scale.

A is the body of the furnace, made of fire-brick or any approved material.

B is the reducing-chamber, into which the ore is charged. b represents grate-bars of refractory material at the bottom of said chambers.

b' is a door in the side of the furnace above the grate-surface, through which the cinders can be withdrawn.

The chamber B is closed at top by a cover b², carrying a hopper b³, through which coke and other material can be supplied to

the chamber during the process of reduction, said hopper having a removable cover b⁴ at the top and a dumping-gate b⁵ at or near its bottom, so that after the material has been charged into the hopper the cover b⁴ can be closed before the gate b⁵ is opened, thus preventing cold air from entering the chamber B through the hopper.

C represents charcoal-chambers formed in the furnace-walls at or near the top of the chamber B and communicating with the latter, as shown. These charcoal-chambers are provided each with a grate c, a door c', through which charcoal or other fuel can be supplied to the chamber above the grate c, and a door c² below the grate, through which air can enter, said air on its way to the reduction-chamber B being compelled to pass up through the burning fuel on the grate c and being thus highly heated before it can enter the reduction-chamber. These chambers C, are in effect, air-flues, through which atmospheric air is drawn from the outside into the reduction-chamber and is heated during its passage through such flues.

Below the reduction-chamber is the matte-chamber D. This chamber, which is shown open at the front in Fig. 2, is when the furnace is in operation closed at this point by slabs d of fire-clay or other refractory material luted into place, as indicated in Fig. 1, said slabs being provided with the usual peep-holes, through which observations may be taken. The matte-chamber contains the molten-metal receiver E, Figs. 1, 3, made of or lined with suitable refractory material, which receiver is supported above the bottom of the chamber on side supports d', which may have the form of rails, as shown, the bottom of the receiver E being formed with corresponding rails e to fit on side rails d', and then allow the receiver to be readily drawn out from or pushed into the matte-chamber. There is a communicating space in the matte-chamber above, below, and at the front of the receiver E, forming a passage through which the heat and flame and other products of combustion pass over, down in front of, and thence underneath the receiver, which is thus subjected to intense heat on all sides. From

the rear of the matte-chamber at a point below the receiver the products of combustion pass through an opening d^2 into a flue F, and thence to the suction-fan G, Fig. 1, which 5 discharges into the chimney-stack H. By this fan a downdraft is created and maintained in the reduction-chamber B and matte-chamber D.

Extending down into the reduction-chamber B through the cover b^2 are pipes i, through which the gas which we prefer to employ in our present process—a highly-oxygenated hydrocarbon gas—is discharged into the said chamber. We prefer to make these pipes 15 flexible, and therefore they are vertically movable or adjustable, so that the position of their discharge ends or nozzles relatively to the charge in the chamber can be varied at will. The pipes i, provided with regulating 20 valves or cocks i', Fig. 5, connect with pipe j, leading from the gasometer J, containing the gas. Another pipe j' leads from the gasometer to pipes or nozzles k, (Figs. 1, 4, 6,) which enter the matte-chamber D from the rear and so 25 as to discharge above the receiver E therein.

In the present instance the gas is obtained by forcing (by means of an air-pump K, Fig. 1, and connecting-pipe l) atmospheric air through a receptacle L, containing a solution 30 of ingredients which when air is passed through the same will impregnate and combine with said air, so as to oxygenate it and in effect to convert it into a highly-oxygenated gas, and as we find it desirable also to 35 charge the same with a fuel gas or vapor we pass it (by a pipe m) on its way to the gasometer through a holder M, containing gasolene or the like, whence it passes by pipe n to the gasometer.

40 N is a tank from which the gasolene is supplied to the holder M.

The charcoal-chambers C are designed to ignite the charge in the reduction-chamber B and also to heat the atmospheric air, which at 45 the roasting stage of the process of reduction is admitted through them into the reduction-chamber. After the reduction-chamber is charged with ore mixed with charcoal and the charcoal-chambers have been filled with 50 charcoal the furnace is tightly closed, excepting the doors c^2 of the charcoal-chambers, which remain open, and the suction-fan is started, thus creating a downdraft, the course of which through the furnace is indicated by 55 the arrows in Fig. 1. As soon as the charge in the reduction-chamber has become fairly ignited gas in limited quantity is admitted through pipes i, which meets and mingles with the heated atmospheric air drawn in 60 through the charcoal-chambers. This continues during the roasting stage of the proc-

ess. When the smelting stage is reached, the doors c^2 of the charcoal-chambers are closed and full head of gas from pipes i is turned on to produce smelting heat. As soon 65 as the metal begins to run into the matte-chamber below the gas-jets k there are turned on also, thus reinforcing and intensifying the heat in the matte-chamber sufficiently to bring the molten mass in the receiver E to a 70 boil. It is in this way that the molten mass is purified and concentrated, the result being the production of a high-grade uniform matte. E', Figs. 1, 2, is a vessel into which the purified molten metal may overflow from the receiver E. 75

Further and more detailed description of the process is unnecessary, inasmuch as it is not here claimed, but, as before said, forms the subject of our companion application of 80 even date herewith, in which it is fully set forth and explained.

Having described our improvement and the best way now known to us of carrying the same into effect, what we here claim as new, 85 and desire to secure by Letters Patent, is—

1. Apparatus for treating ores, comprising a reduction-chamber; a matte-chamber below and communicating with the reduction-chamber; means for creating and maintaining a 90 downdraft through the reduction and then through the matte-chamber, charcoal-chambers C communicating with the upper part of said reduction-chamber; gas-jets located in both the reduction-chamber and the matte-chamber; and a source of supply of gas under pressure having controllable communication with said gas-jets, substantially as and for the purposes hereinbefore set forth. 95

2. A furnace for the treatment of ores having a reduction-chamber; charcoal-chambers C communicating with the upper portion of said reduction-chamber; a matte-chamber below the reduction-chamber; a molten-metal receiver in said matte-chamber; means for creating and maintaining a downdraft in said furnace, downward through the reduction-chamber thence down, into and through the matte-chamber and around the receiver therein, and thence out from the furnace, 110 and means for introducing gas into both the reduction-chamber and the matte-chamber, substantially as and for the purposes hereinbefore set forth. 115

In testimony whereof we have hereunto set our hands this 5th day of February, 1902.

ANDREW M. DORR.
JOSEPH SPANG.
